UNITED STATES PATENT OFFICE.

ROBERT D. TACKABERRY, OF LEWISTON, MAINE.

AUTOMATIC VALVE MECHANISM.

Application filed March 28, 1922. Serial No. 547,555.

To all whom it may concern:

Be it known that ROBERT D. TACKABERRY, a citizen of the United States, residing at Lewiston, county of Androscoggin, Maine, has invented certain new and useful Improvements in Automatic Valve Mechanism, of which the following is a specification.

This invention relates to automatic valve mechanism, and is particularly adapted for use in controlling the flow of steam to the kiers or tanks in which cloth or other material is boiled. For the purpose of this application, therefore, I shall show and describe my invention in its adaptation to this particular field, although it will be understood that such showing is purely illustrative and no way limiting, and that my automatic valve mechanism may be used in a variety of adaptations to control the flow of any fluid.

The object of my invention is to provide in a simple and inexpensive form an automatic valve mechanism which will be positive and reliable in operation and capable of ready assembly and disassembly, for the purposes of cleaning or making repairs, and which will permit the period of flow of the fluid to be automatically varied according to the requirements of the particular machine or apparatus to which the valve mechanism is applied.

This object, together with certain features of advantage which will appear more particularly hereinafter, is secured in the device of the present invention.

The construction and operation of my invention, together with a selected embodiment which well illustrates the principles involved, are described and shown in the accompanying specification and drawings and the characteristic features of novelty are particularly pointed out in the appended claims. Throughout the specification and drawings like reference characters are correspondingly applied, and in the drawings:

Fig. 1 is an elevation, partly broken away, showing an automatic valve mechanism in accordance with my invention applied to the steam system of a boiling kier or tank.

Fig. 2 is a side elevation of the valve mechanism.

Fig. 3 is a front elevation at the inlet end of the valve and particularly showing the driving mechanism for imparting an oscillating motion to the valve.

55

Fig. 4 is an enlarged longitudinal section of the valve.

Fig. 5 is a view corresponding to Fig. 3 and showing an arrangement for simultaneously operating a bank of valves each adapted to control an individual kier.

Figs. 6 and 6^a are diagrams illustrating the operation of a single valve.

Fig. 7 is a face view of the valve disc.

Fig. 8 is a face view of the valve seat, and

Fig. 9 is a detail view of a device for distributing the fluid uniformly over the contents of the kier.

My variable time valve mechanism is mounted in the steam system of the boiling kier or other apparatus under control and is operated at predetermined intervals or constantly, as determined by the driving and regulating devices, to permit and prevent the passage of steam to the kier. The regulating device enables the open and closed periods of the valve to be varied as circumstances may require and comprises a loose and a fast clutch element on the valve stem. The loose clutch element is operatively connected with the driving mechanism and transmits the actuation thereof to the fast clutch element and thus to the valve stem, which is thereby turned to move the valve thereon relative to its seat to permit or prevent the passage of the fluid through ports in the valve and seat, according to whether or not said ports are in registry.

I have indicated at 1 and 2 the parts of a two-part valve casing which are bolted together as appears in Fig. 4, and enclose a valve disc 3. The disc 3 is fast on the inner end of a valve stem 4 which is journaled through the outer casing part 1 in fluid tight relation thereto, as indicated at 5 and 5^a in said figure. The inner casing part 3 is recessed to contain a removable valve seat 6 which is held against rotation relative to the casing part 1 by a pin 7. The seat 6 has a central hole 8 providing a bearing for the inner end of the valve stem 4 and below said hole has an extended port 9 with which

a relatively small port 10 in the valve 3 is adapted to register, as will be more fully explained hereinafter.

The fluid to be controlled is admitted into the chamber of the valve casing in advance of the valve 3 through an inlet pipe 11 which is threaded into a hole tapped into the under side of the casing part 1 and said fluid after passing through the ports 9 and 10, when said ports are in registry, is delivered from the valve casing through an outlet pipe 12 which is threaded into a hole tapped into the casing part 2.

The port 10 in the valve disc 3 is of equal area to the delivery opening of the supply pipe 11. The port 9 in the valve seat 6 is equal in radial dimension to the radial dimension of the port 10 and the length of its arc is equal to the complete passage of said port from one extreme of its oscillation to the opposite extreme.

The valve disc 3 is adapted to be automatically oscillated relative to its seat from a timer shaft 16' and the open and closed periods of the valve are automatically regulated by a collar 13 loose upon the valve stem 4 and having an integral lever arm 14 adapted to be connected in any suitable manner as by a connecting rod 15 and a crank arm 16 with the timer shaft 16' of a suitable timing mechanism, as an electric motor, which is directly connected to said shaft through a reducing gear train.

As here shown, the relative lengths of the lever arm 14, and crank 16 are so proportioned that the lever will move through an arc of 130° and return to its original position while the crank is describing one complete revolution. Obviously, of course, this ratio may be varied as conditions may require.

The rotative motion of the crank 16 is thus transmitted to the lever arm 14 as oscillatory motion effective to rotate the collar 13 relative to a fast collar 17 which is keyed to the valve stem as indicated at 18 and 18'. The opposing faces of the collars 13 and 17 are provided with ratchet teeth 19 which intermesh so that the motion of the collar 13 is applied to the collar 17 and through the key 18 to the stem 4 whereby to turn the valve disc 3 relative to its seat 6.

The collar 17 preferably has two keyways 18' located at opposite sides of the stem and the key 18 is designed to engage in either of said keyways and is of such a length that the collar 17 may be moved outwardly and turned so that the key will prevent it from engaging the collar thereby rendering the valve inoperative. By having two keyways in the collar 17 and locating said keyways on opposite sides of the stem, the stem 4 and disc 3 of certain of the valve units may be turned through a half revolution relative to their respective

seats 6 whereby to insure that such valve units will work in opposition to other valve units when the automatic mechanism is employed in a bank of valves as illustrated in Fig. 5, thus permitting a steady flow of the fluid or gas into the supply main. As an alternative adjustment, the seats 6 may be moved relative to the valve discs to accomplish this result.

The fast collar 17 is backed by a coil spring 22 which is confined about the valve stem 4 between said collar 17 and a retaining collar 23 applied to the outer end of said stem, and serves to maintain the collars 13 and 17 in engagement. Mounted on the collar 13 is a dial 27 which in conjunction with a pointer 28 on collar 17 indicates the time during which the valve will remain open as governed by the relative positions of the disc and seat.

When arranged in series as shown in Fig. 5, the collar 13 of each individual valve stem is provided with an arm 20 and said arms are connected to a common motion transmitting connection 21 whereby the motion of the crank 16 as applied to the arm 14 of the nearest collar 13 in the bank of valve units will be simultaneously transmitted to all of the valve stems through said arm 20 and common motion transmitting connection 21.

Lubricant is supplied to all bearings for the valve stem from a lubricating cup 24 which is mounted in the outer end of a longitudinal passage 25 in the valve stem. Passage 25 is provided with branch passages 26 leading to the several bearings for said stem.

In Fig. 1 one of my automatic valve units is shown as mounted in the steam system of a boiling kier or tank 30. In such installation an injector 32 is usually arranged in the pipe line 12' leading from the under side of the kier and with its direction of flow into a pipe 33 returning to the top of the kier, whereby to keep the contents of the kier in circulation.

Mounted within the kier on a shaft 34 depending from the top thereof is a disc 35 which is provided on both faces with sets of fins or blades 36 and 36' (see Fig. 9) radiating from the center thereof and with intermediate holes 37. The incoming fluid contacts the upper blade series 36 and imparts a whirling motion to the distributor, then the fluid passes through the holes 37 and is distributed uniformly over the contents of the kier by the lower blade series 36'. The blade series 36 on the upper face of the disc are curved in the opposite direction to the other blade series 36' on the lower disc face.

The operation is as follows: With the valve disc 3 disposed in such position as to bring its port 10 in the relation indicated at A, Fig. 6a, to the port 9 of the valve seat

6 and with a head of steam under pressure admitted through the inlet 11 into the valve chamber and holding the valve 3 firmly against its seat, motion is given to the crank

5 16 in the counter clockwise direction of the arrow, Fig. 3, and this motion is transmitted through the connections 15 and 14 to the loose collar 13.

The crank 16 starts from the position A, 10 Fig. 3, and the rotation thereof is applied as oscillatory movement to the valve stem through the engagement of the teeth 19 of the collar 13 with the teeth of the first collar 17, and the valve disc 3 moves counterclockwise in Fig. 6^a from the position A to the position B in said figure during the travel of the crank from position A to position B in Fig. 3. The ports 10 and 9 are now in register and the steam passes through 15 said ports into outlet pipe 12. When the crank reaches the position B, Fig. 3, the valve disc has reached the limit of its counterclockwise travel, and as the crank continues its rotation, the disc reverses its 20 direction and commences to move clockwise back to its original position A reaching such position when the crank reaches position A', Fig. 3, at which point the crank has described approximately one half a revolution. This is the open period of the valve.

The crank 16 then passes through the upper half of its revolution and as it travels from position A', Fig. 3, to position C, the port 10 of the valve disc 3 is moved clockwise in Fig. 6^a from position A to position C. As the crank continues its rotation from position C to the starting point A, Fig. 3, the disc 3 reverses its direction and moves back to the starting point A, Fig. 6^a. During 25 the travel of the port 10 from position A to position C and return, said port is opposite the solid portion of the valve seat, and the crank has described approximately one half a revolution. This is the closed period 30 of the valve.

As described and illustrated herein the open and closed periods of the valve are equal but obviously any desired ration may be obtained. A convenient method of varying the ration consists in drawing the collar 17 away from the collar 13 and rotating said collar 17 by hand in either direction so that the port 10 will occupy a position with relation to the port 9, either above or below 35 the relation hereinbefore described, thereby increasing or decreasing as the case may be, the open period of the valve.

Such an adjustment is indicated diagrammatically in Fig. 6, wherin the valve disc is 40 represented as having been moved manually through approximately 90° to the point D in said figure, so that when the disc is set in motion, the port travels to position E, and returns to position D and from position D 45 to position F and return to D, and hence the

valve is constantly open. Obviously, by turning the disc through another arc of 180° the valve will be constantly closed.

As contemplated herein, the collars 13 and 17 each have an annular series of twenty teeth thereby enabling the valve to operate in ten different positions by changing the relative relation of the collars to each other through one half circumference. Obviously, of course, the number of teeth may be varied at will. The total elapsed time period for one complete oscillation of the valve may be varied at will by varying the speed of the motor or other drive for 50 the crank 16.

After passing through the valve 3, Fig. 1, the steam flows along the pipe 12 into the injector 32 where it mingles with the water returning by gravity along pipe 12' from the kier 30, and the mixture is returned by 55 the injector through the riser pipe 33 to the top of the kier for circulation. In entering the kier the fluid contacts the rotary distributor 35 and is thrown uniformly over 60 the contents of the kier.

Various modifications in the form and construction of my device may obviously be resorted to without departing from the spirit of my invention if within the limits 65 of the appended claims.

What I therefore claim and desire to secure by Letters Patent is:

1. An automatic valve mechanism, comprising relatively movable valve and seat members having ports adapted to register, a rotatable timer, and operative connections from said timer to said valve effective to transmit the rotary motion of said timer to the valve as oscillatory motion and comprising a fast and a loose clutch element 100 adapted to engage with each other, and a crank connection between said loose clutch element and said timer.

2. An automatic valve mechanism, comprising a valve seat, a valve stem having a valve movable relative to said seat, said valve and seat having ports adapted to register, a rotatable timer, and operative connections from said timer to said valve effective to transmit the rotary motion of 110 said timer to the valve as oscillatory motion and comprising a fast and a loose clutch element on said valve stem, adapted to engage with each other, an arm carried by said loose clutch, and a crank connection 115 from said arm to said timer.

3. An automatic valve mechanism, comprising a valve seat, a stem having a valve movable relative to said seat, said seat and valve having ports adapted to register, a rotatable timer, operative connections from 120 said timer to said valve stem effective to transmit the rotary motion of said timer to the valve as oscillatory motion and including a fast and a loose collar on said stem 125 130

having teeth adapted to intermesh, a spring normally urging said collars towards each other, an arm fast to said loose collar, and a connecting rod and crank from said arm to said timer.

4. An automatic valve mechanism, comprising a valve seat, a stem having a valve movable relative to said seat, said seat and valve having ports adapted to register, a rotatable timer, operative connections from said timer to said valve stem effective to transmit the rotary motion of said timer to the valve as oscillatory motion and including a fast and a loose collar on said stem having teeth adapted to intermesh, a spring normally urging said collars towards each other, an arm fast to said loose collar, and a connecting rod and crank from said arm to said timer and said fast collar having a pair of keyways at opposite sides of the stem, and a key effectively engageable with either keyway and of a length sufficient to hold the collar out of engagement with the

loose collar when the fast collar is moved longitudinally of the stem and turned 25 through a partial revolution.

5. An automatic valve mechanism, comprising a valve seat, a stem having a valve movable relative to said seat, said seat and valve having ports adapted to register, a 30 rotatable timer, operative connections from said timer to said valve stem effective to transmit the rotary motion of said timer to the valve as oscillatory motion and including a fast and a loose collar on said stem 35 having teeth adapted to intermesh, a spring normally urging said collars towards each other, an arm fast to said loose collar, and a connecting rod and crank from said arm to said timer, and a dial carried by said 40 loose collar and a pointer carried by said fast collar.

In testimony whereof I affix my signature.

ROBERT D. TACKABERRY.
